UNITED STATES PATENT OFFICE.

BENJAMIN R. SMITH, OF PHILADELPHIA, PENNSYLVANIA.

INSTRUMENT FOR ASCERTAINING THE DIRECTION OF SOUNDS IN FOG, &c.

Specification of Letters Patent No. 23,718, dated April 19, 1859.

To all whom it may concern:

Be it known that I, BENJAMIN R. SMITH, or the city and county of Philadelphia and State of Pennsylvania, have invented or discovered a new and useful improvement in the mode of correctly ascertaining the direction of sounds at sea in foggy or thick weather, as, for instance, the ringing of a fog-bell, and at the same time of so concentrating any sound, either from this or other sources, that it may be heard at greater distances than by the naked ear, or at a given distance the intensity greatly increased; and I do hereby declare the following to be a full, clear, and exact description of the same, reference being had to the accompanying drawings, making a part of this specification, in which—

Figure 1 represents the front of a parabolic reflector, and Fig. 2 represents a section through the same, which two figures will fully illustrate my invention or discovery.

It is a great desideratum for persons at sea, to be able to judge correctly of the direction of sounds, in a fog, or other thick weather, as it is utterly impossible to determine, judging by the unassisted ear, whether the sound of a fog bell, for instance, comes from the right or left hand side, so that these only serve to warn of danger without showing its position.

By using a parabolic reflector of the proper size, and applying the ear to its focus, the intensity of the sound will reach its maximum, when the reflector is pointing directly toward the bell, or in other words, when the rays of sound are entering on a line with the axis of the curve—I thus ascertain the position of a fog bell, or other source of sound, and at the same time hear it more distinctly at a given distance, or at a greater distance with the same distinctness, and this constitutes my invention.

The principle of the invention is fully illustrated in the parabolic reflectors used in light houses and the law which is good in acoustics as in optics, that the angles of incidence and reflection are equal. But while a parabolic form is the best, I do not confine my invention to that form alone, but mean to claim any form of curve that will collect the rays or waves of sound to a focus, point, or center, where the ear may be placed, and when all the sound entering the reflector

is converged to this focus, or center, that is, when it reaches its greatest intensity then will the reflector be pointing directly toward the source of the sound.

To enable others skilled in the art, to make and use my invention I will proceed to describe the same by reference to the drawings.

In Fig. 2, suppose the line a, b , to represent a parabola, and a, c , the axis— d , being the focus of the parabolic curve. Now if from the point d , lines be drawn to any points $e, e', e'', e''', \&c.$, and from these points lines parallel with the axis a, c , as at $f, f', f'', f''', \&c.$, be drawn, it will represent how the waves or rays of sound, coming in the direction of the lines $f, f', f'', \&c.$, will be reflected at an angle equal to that at which they strike the parabola, and be brought to the focus d ; and at this point an opening is made, fitted with an ear piece n which is held to the ear of the listener—a handle m being provided for this purpose.

It may be doubted whether in a heavy blow, this instrument would be available, for the purpose. But in a gale of wind, a fog bell in many cases can not be heard at all, and when a fog bell is of any service, then this reflector will not only detect its position, but will increase its vibrations on the ear, so that the sound may be heard at a greater distance than without it. The reverse, exactly, of this effect and operation would take place were a bell to be hung in the focus of a parabolic reflector, for the waves of sound would then be thrown in a given direction in obedience to the law of the angle of incidence being equal to the angle of reflection, and by this means the sound of the bell or whistle would be thrown off in lines parallel to each other or as nearly so as may be expedient and thus the body of the sound carried to a much greater distance than is at present the case.

The curved portion of the reflector may be made of metal of any kind, and the part a, c , may be of thin wood, or it may be entirely of metal, or any other material sufficiently light and strong, and that will reflect the waves or rays of sound.

Having thus fully described the nature and object of my invention, what I claim as new, and desire to secure by Letters Patent, is,

A reflector made of suitable material, and

of such a form or shape that it will collect all the rays or waves of sound entering it, to a focus, when it may be pointed toward the direction from whence the sound comes, 5 for the purpose of ascertaining the direction of the source of such sound, and conversely, of throwing off from a reflector, in parallel

lines, if need be, the sound of a bell or whistle which may be placed at the focus of the said reflector, substantially as described. 10

BENJAMIN R. SMITH.
